UNITED STATES PATENT OFFICE.

JOHN EDWARD BAKER, OF SAND SPRINGS, OKLAHOMA.

ANTICREEPING DEVICE FOR TRACK-RAILS.

1,235,349.

Specification of Letters Patent. Patented Feb. 12, 1918.

Application filed January 12, 1917. Serial No. 141,958.

To all whom it may concern:

Be it known that I, JOHN EDWARD BAKER, a citizen of the United States, residing at Sand Springs, in the county of Tulsa and State of Oklahoma, have invented certain new and useful Improvements in Anticreeping Devices for Track-Rails; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to an anti-creeping device for track rails, and more particularly to a device for use on rails leading to or from a track scale, the principal object of the invention being to prevent creeping of the rails into a scale pit and resultant interference with the scale.

In accomplishing this object I have provided improved details of structure, the preferred forms of which are illustrated in the accompanying drawings, wherein:—

Figure I is a perspective view of an anti-creeping device containing my improvements, illustrating its combination with a track rail, one of the keeper plates broken away to better illustrate the parts.

Fig. II is a side elevation of part of a track rail, illustrating its location on a pit wall and showing the combination of a scale platform and its track rail with a ground rail.

Fig. III is a plan view of a chair block, one of the keeper plates being removed to show the gripping jaw and illustrate the taper of the jaw and its seat.

Fig. IV is a cross section of the device.

Fig. V is a detail perspective view of one of the jaws.

Referring more in detail to the drawings, and first to the mounting of the track rails and their combination with the scale pit and platform, 1 designates a concrete pit wall, 2 track ties for supporting a ground rail, 3 a ground rail supported on the ties and attached thereto by the spikes 4, 5 a scale platform and 6 a track rail carried by the platform in alinement with the ground rail 3, the track and ground rails being spaced to provide for free vertical movement of the platform rail.

While it is essential that the track and

platform rails be located in as close relation as possible in order to limit the break between the ends thereof, it is apparent that longitudinal movement of either of the rails 60 might project the end of the rail over one of the movable parts to an extent that might interfere with or prevent the operation of the platform. It is well known that such longitudinal displacement of track rails is 65 occasioned generally by the thrust of the rails due to varying temperatures, and that such displacement may be to a material extent and sufficient to project a ground track rail into a scale pit to a distance that would 70 materially interfere with or entirely prevent the operation of the scale.

In order to overcome this disadvantage and at the same time avoid interference with natural expansion and contraction of 75 the rail, I have provided the anti-creeping device, which is so located with respect to the scale as to permit expansion or creeping away from the pit and prevent like action 80 in the direction of the pit.

The device for accomplishing this purpose comprises the chair block 8, having up-standing edge flanges 9 and an upstanding intermediate rail seat 10 forming down-set jaw seats 11 at opposite sides of the rail 85 seat 10, the edge flanges being spaced to receive the base of a track rail therebetween and tapered on their inner faces to form a wedge like opening for the purpose previously described.

The bottom of the chair block is provided with the tapered rib 12, having a heel 13 at the front end of the chair for abutment against a pit wall or other obstruction.

The flange 9 of the chair block are spaced a greater distance than the width of the rail seat, so that the edges of the rail base may overlie the jaw seats 11 to be engaged by the jaws 15 which are adapted for location within the seats. Each of the jaws is tapered at its outer side correspondingly to the taper of the inner edges of the flanges 9 to locate the tapered inner edges of the said jaws parallel with each other, and with the edges of the track rail, the inner edges 100 of the jaws being provided with teeth 17 which are adapted for gripping the edges of the rail base, so that when the rail is seated in the chair with the edges of the base in engagement with the jaws, movement of the rail toward the front of the chair will induce a gripping action of the 105 110

2
jaws thereon that will tend to carry the jaws along with the rails until such movement is prevented by the wedging of the jaws against the chair flanges.

5 In order to support the chair on a track rail and retain the gripping jaws in their seats, I provide keeper plates 19, which are adapted for seating on the upper edges of the flanges 9 and for attachment thereto by 10 cap screws 20 which pass through the keeper plates into the apertures 21 in the chair flanges to firmly attach the keeper plates to the flanges and effect a support of the device on the track rail, the plates 19 extending inwardly beyond the edges of the flanges to overlie the jaws and the edges of the rail base to mount the device on the rail and confine the jaws.

In using the device, assuming the same to 20 be constructed as described, and assuming the use in connection with a platform scale, a seat 3 with the jaws in their seats 11, is mounted on the base of the ground rail by the keeper plates as described, and the end 25 of the chair with its heel 13 moved against the outer face of the pit wall 1 to form an abutment for the chair that will prevent any material movement thereof in the direction of the pit.

30 With the device so located, the jaws are driven to close contact with the edges of the track rail base and with the inner walls of the chair flanges 9. With the parts so arranged, should there be any tendency of 35 the rail to creep in the direction of the pit, movement of the rail toward the pit will tend to drive the jaws 13 in the same direction. This movement is, however, resisted by the tapered walls of the seat rails, the 40 action being that of a wedge and the gripping tendency increasing with any increase in movement of the rail in the direction of the pit, the gripping of the rail by the jaws being induced by the abutment of the seat 45 against the pit wall which takes the creeping thrust of the rail through the seat 8. While movement of the rail in the direction of the pit is prevented by the device as described, its movement in the other direction 50 is not interfered with, as such movement would tend to pull the jaws away from their seats and loosen the same in the chair, thereby obviating any interference with natural 55 expansion and contraction of the rail.

While I have described the device in a

specific combination with a track scale, it is apparent that the scope of the invention is not so limited, as the device will accomplish its purpose in combination with the track rails of any other track device, or it 60 may be used if desired for splicing the ends of adjacent rails.

Having thus described my invention what I claim as new therein and desire to secure by Letters-Patent, is:—

65 1. An anti-creeping device for track rails comprising a chair adapted for abutment against a fixed body at one end and having upstanding side flanges and an intermediate, upstanding rail seat, forming jaw seats at 70 opposite sides of the chair and adjacent the flanges, and jaws located in the jaw seats and adapted for engaging the edge of a rail base.

2. An anti-creeping device for track rails 75 comprising a chair adapted for abutment against a fixed body at one end and having upstanding side flanges and an intermediate, upstanding rail seat, forming jaw seats at 80 opposite sides of the chair and adjacent the flanges, jaws located in the jaw seats and adapted for engaging the edge of a rail base, and keeper members on the upper faces of the seat flanges projecting over the jaw seats to overlie a rail base and support the 85 said seat therefrom.

3. A device of the character described comprising a chair provided with upstanding edge flanges forming a rail seat and having convergent inner faces, jaws having 90 outer edges tapered correspondingly to the inner faces of said flanges and having teeth at their inner edges, and keeper plates removably mounted on said flanges for confining the jaws and overlying a rail base to 95 support the device.

4. A device of the character described comprising a chair having an abutment neel at one end and provided with upstanding edge flanges forming a rail seat and having 100 convergent inner faces, jaws having outer faces tapered correspondingly to the inner faces of said flanges and having teeth at their opposite edges, and keeper plates removably mounted on said flanges for confining the jaws and overlying a rail base to 105 support the device.

In testimony whereof I affix my signature.

JOHN EDWARD BAKER.
